DRESSING TOOL HOLDER

Casper Kreutzer, Milltown, N. J.

Application April 15, 1947, Serial No. 741,552

2 Claims. (Cl. 51—205)

1

This invention relates to improvements in hand tools for use in dressing and truing the operative faces and peripheries of grinding wheels, such as emery wheels and the like, and for similar purposes; and the invention has reference, more particularly, to a novel means for holding a dressing tool, such e. g. as a block of "Carborundum," when applying the same to a grinding wheel to be dressed therewith.

The invention has for an object to provide a novel holder in which a block of "Carborundum" or like tool element can be clamped, whereby to project the operative end of said tool element therefrom, and so that the tool element may be safely manipulated in use.

The invention has for a further object to provide a simple, inexpensive and yet very efficient holder for the stated purposes, the same including novel tool element clamping means which is adjustably movable in and along the holder body, so as to accommodate the holder for use with various lengths of tool elements, whereby even tool elements of lengths so short as to prohibit safe handling of the same per se, may nevertheless, when mounted and clamped in the holder, be firmly held and safely manipulated in use by means of the holder, and consequently the life of tool elements, as worn down by use, may be economically prolonged.

Other objects of this invention, not at this time more particularly enumerated, will be understood from the following detailed description of the same.

An illustrative embodiment of the invention is shown in the accompanying drawings, in which:

Fig. 1 is a perspective view of the novel dressing tool holder made according to the invention; Fig. 2 is a top face view of the same; Fig. 3 is a cross sectional view, taken on line 3—3 in Fig. 1; Fig. 4 is a longitudinal sectional view, taken on line 4—4 in Fig. 1; and Fig. 5 is a perspective view of the tool element clamp member of the holder.

Similar characters of reference are employed in the above described views, to indicate corresponding parts.

Referring to the drawings, the novel tool holder comprises an endwise open or tubular body, preferably but not necessarily of polygonal cross sectional shape, comprising a top wall 10, side walls 11 and a bottom wall 12. The top and bottom walls 10 and 12 of the holder body are respectively provided with longitudinal slotways 13 and 14. Arranged within the interior of the

body is a clamp member. Said clamp member is of angular formation whereby to provide a substantially horizontal clamp jaw section 15 and a perpendicular leg section 16 which depends from the rearward end of the clamp jaw section 15. The clamp jaw section 15 underlies the top wall 10 of the holder body, and normally extends in plane parallel thereto, while the foot 17 of the depending leg section 16 bears upon the inner face of the bottom wall 12 of the holder body, so as to fulcrum the clamp member for tilting movement, as and for the purpose subsequently herein described. Said clamp jaw section 15 is provided, for projection from its upper face and outwardly through the slotway 13 of the top wall of the holder body, with a thrust lug 18 which forms a unitary part of said clamp jaw section 15. Extending perpendicularly through the clamp jaw section 15 and its thrust lug 18 is an opening or passage 19. Disposed to extend upwardly through the slotway 14 of the bottom wall 12 of the holder body and thence through the interior of said holder body to pass through the opening or passage 19 of the clamp jaw section 15 and its thrust lug 18, so as to project exteriorly from the latter and exteriorly of the holder body, is a draw bolt 20, the head 21 of which abuts, preferably through an interposed washer 22, the exterior face of said bottom wall 12 of the holder body. Threaded onto the upper screw-threaded end portion 23 of said draw bolt 20 is a thumb or wing nut 24 which abuts, preferably through an interposed washer 25, the outer end of the thrust lug 18 of said clamp jaw section 15. Mounted around the draw bolt 20, intermediate the bottom wall 12 of the holder body and the under side of said clamp jaw section 15, is a compression spring 26. Said compression spring 26 yieldably urges the clamp member to a normal initial position, whereby to dispose the clamp jaw section 15 in an uplifted released position abutting and parallel to the top wall 10 of the holder body.

As illustratively shown, the tool element to be served by the holder comprises a block 27 of abrasive material, such e. g. as "Carborundum." Said tool block is inserted through the forward open end of the holder so as to extend rearwardly thereinto, with its rearward end portion 28 disposed to underlie the clamp jaw section 15 of the clamp member. It will be obvious that the clamp member can be moved forward or rearward through the slotways 13—14, as may in any given case be required, whereby to dispose the same in such position as to operatively engage the

clamp jaw section 15 over the said rear end portion 28 of the tool block 27, while at the same time allowing free outward projection, from the forward end of the holder, of a desired amount of the tool block which is to serve as an operative portion thereof.

The tool block 27 having been disposed in the holder, and the clamp member adjusted in position for operative engagement therewith, the thumb or wing nut 24 is screwed downward on the draw bolt 20 so as to thrust downwardly upon the thrust lug 18 of the clamp member. Such downward thrust upon the thrust lug 18 produces a down tilting movement of the clamp jaw section 15; this down tilting movement being fulcrumed by the clamp leg section 16 which pivots on the foot 17 thereof by reason of the bearing of the latter on the bottom wall 12 of the holder. The tilting movement of the clamp member causes the free end of the clamp jaw section 15 to swing down upon the rear end portion 28 of the tool block 27, thus firmly clamping and gripping said end portion 28 between said clamp jaw section and the bottom wall 12 of the holder (see Fig. 4).

When thus clamped to the holder, the tool block 27 will be securely and immovably held in fixed relation to the holder against accidental shift or displacement, and consequently the holder can thereupon be used as a means for manipulating the tool block for operative application of the latter to a grinding wheel or the like desired to be treated thereby.

It will be obvious that, as the operative end of the tool block 27 wears down in use, the tool block can be adjustably advanced relative to the holder by relaxing the clamp member and thereupon sliding the same and the tool block forwardly relative to the holder, and then again tightening home the clamp member into gripping relation to the tool block. It will thus be seen that practical use of the tool block may be continued until the same is almost entirely consumed, and that consequently the useful life of said tool block can be greatly prolonged. From this it will be clear that not only is economy of tool material gained, but the holder also provides means for safely manipulating, in use, short tool block portions without risk of injury to the user's hands.

From the above description it will be evident that the novel holder of this invention provides a practical device for the intended purposes.

Having now described my invention, I claim:

1. A tool holder for the purposes described comprising an endwise open holder body having aligned slotways in opposite walls thereof, said

holder body being adapted to receive an abrasive tool element by insertion of the latter thereinto through an open end of the same, a tiltable clamping means slidably related to said holder

body behind the inserted tool element and adapted for adjustment toward and from said inserted tool element, said clamping means including a clamp-jaw section to engage the inserted end of said tool element, means for yieldably urging said clamp-jaw section to released position, and manipulatable means slidably movable in said slotways for tilting said clamping means whereby to engage said clamp-jaw section in gripping relation to the inserted tool element.

2. A tool holder for the purposes described comprising an endwise open holder body having aligned slotways in opposite walls thereof, said holder body being adapted to receive an abrasive tool element by insertion of the latter thereinto through an open end of the same, a tiltable clamping means slidably related to said holder body for adjustment toward and from the tool element receiving end of the latter, said clamping

means comprising a clamp jaw section contiguous to one slotted wall of said holder body and a dependent fulcruming leg section footed upon the opposite slotted wall of said holder body, said clamp jaw section having a thrust

lug exteriorly projecting through the slotway of the adjacent wall of said holder body, a draw bolt extending through the slotways of said holder body and through the clamp jaw section and its thrust lug, spring means for yieldably holding said clamping means in released position, and nut means threaded on an exterior end of said draw bolt and being manipulatable to thrust against said thrust lug, whereby to tilt said clamping means so as to move its clamp jaw section into gripping relation to the inserted tool element.
